United States Patent Office

Des. 202,614
Patented Oct. 26, 1965

202,614

BUILDING UNIT

Ira M. Koger, 4539 Beach Blvd., Jacksonville, Fla.

Filed Dec. 11, 1964, Ser. No. 82,999

Term of patent 14 years

(Cl. D13—1)

FIG. 4

FIG. 1

FIG. 2

FIG. 3

FIG. 1 is a plan view of the top of the building unit;
FIG. 2 is a front elevation of the building unit;
FIG. 3 is a side elevation of the building unit; and
FIG. 4 is an enlarged plan view of the building unit
with the roof removed to show the interior room layout.
I claim:
The ornamental design for a building unit, as shown.
